UNITED STATES PATENT OFFICE.

JOSEPH FRAMPTON, OF WILLIS, TEXAS.

RAIL JOINT, CHAIR, AND TIE.

No. 896,001.

Specification of Letters Patent.

Patented Aug. 11, 1908.

Application filed September 25, 1907. Serial No. 394,540.

To all whom it may concern:

Be it known that I, JOSEPH FRAMPTON, a subject of Great Britain, residing at Willis, in the county of Montgomery and State of 5 Texas, have invented new and useful Improvements in Rail Joints, Chairs, and Ties, of which the following is a specification.

This invention relates to rail joints, chairs and ties, and one of the principal objects of 10 the same is to provide simple, reliable and efficient means to prevent the rails from spreading or sinking at the joints.

Another object of the invention is to provide a metal tie designed to pass through the 15 rail chairs at the rail joints, said tie having a rib on the under side thereof which bears at its opposite ends against said chairs.

These and other objects may be attained by means of the construction illustrated in 20 the accompanying drawings in which

Figure 1 is a plan view of a rail joint and tie made in accordance with my invention. Fig. 2 is a side elevation of one of the rail joints. Fig. 3 is a sectional view on the line 25 3—3 of Fig. 1, looking in the direction indicated by the arrow.

Referring to the drawing for a more specific description of my invention the numerals 1 designate the meeting ends of a pair 30 of railway rails and 2, 2 designate the two sections or members of the rail chair. Fish plates 3 are formed on the upper portions of the members 2 and a recess is formed in the chair for the base flange 4 of the rails.

35 A metal tie 5 comprising a flat steel plate is provided with a centrally disposed rib 6 upon its lower side, said rib bearing at its ends against the inner sides of the rail chair as at 7, Fig. 3. The tie 5 extends through the 40 chair members 2 immediately under the joint of the rails and bolts 8 extend vertically through the chair members and

through the tie and are provided with nuts 9 underneath the chair members. Bolts 10 extend through the fish plates 3.

Transverse brace rods 11 extend through the chair members 2 and said rods are threaded at the ends and fitted with nuts 12. Lock nuts 13 are fitted to the rods 11 and bear against the inner sides of the rail chairs 50 as shown in Fig. 1. In lieu of the lock nuts 13 I may use a tube 14 through which the brace rod 11 extends, said tube being of the desired length to reach from one rail chair to the other.

55 From the foregoing it will be obvious that a rail joint and tie made in accordance with my invention will firmly hold the meeting ends of railway rails and will effectively prevent sinking or spreading of the rails at the 60 joints.

Having thus fully described the invention what is claimed as new is:

1. In a device of the character described, rail chairs, comprising inner and outer sections, fish plates formed upon the chair sections, a rail tie extending through the chair sections and bolted thereto, and brace rods extending through said rail chairs, and provided with adjusting nuts.

70 2. In a device of the character described, rail chairs, a rail tie extending through said chairs, brace rods extending through said chairs upon opposite sides of said tie, and tubes through which said brace rods extend, 75 said tubes being disposed between said chairs, and nuts upon the outer ends of said rods.

In testimony whereof I affix my signature in presence of two witnesses.

JOSEPH FRAMPTON.
